UNITED STATES PATENT OFFICE.

FRANK BYRON CHURCHILL, OF LA HARPE, ILLINOIS.

GEARING FOR WASHING-MACHINES AND OTHER APPARATUS.

1,233,026.

Specification of Letters Patent. Patented July 10, 1917.

Application filed July 29, 1916. Serial No. 112,104.

To all whom it may concern:

Be it known that I, FRANK B. CHURCHILL, a citizen of the United States, residing at La Harpe, in the county of Hancock and 5 State of Illinois, have invented a new and useful Gearing for Washing-Machines and other Apparatus, of which the following is a specification.

This invention has reference to gearing 10 for washing machines and other apparatus, and its object is to provide a simple and efficient gearing for use in conjunction with driven or actuated parts particularly of the character where the actuated parts have a 15 rocking movement.

The invention comprises an actuated member mounted for rocking with means constraining it to assume a central or neutral position from which it may be moved in 20 either direction, the constraining means being usually in the form of opposed springs. Power is applied from any suitable source which may in some instances be local to the structure, and this power, through suitable 25 connecting gearing to which rotary motion is imparted by the source of power, is translated into reciprocatory movement ultimately transmitted to the rockable structure for its actuation.

30 The invention is particularly useful in connection with washing machine bodies, and as it is sometimes desirable that such bodies be capable of actuation by hand, provision is made for disconnecting the gearing 35 from the rockable member and the application of a suitable handle thereto, so that the hand actuation may be performed.

The invention will be best understood from a consideration of the following detailed description, taken in connection with 40 the accompanying drawings forming part of this specification, with the further understanding that while the drawings show a practical form of the invention, the latter 45 is not confined to any strict conformity with the showing of the drawings, but may be changed and modified so long as such changes and modifications come within the scope of the appended claims.

50 In the drawings:

Figure 1 is a perspective view of a washing machine with the gearing of the present invention applied thereto.

Fig. 2 is a perspective view of the struc-

ture of Fig. 1 as seen from the diagonally 55 opposite corner.

Fig. 3 is a horizontal section through the frame supporting the gearing.

Fig. 4 is an axial section through a wrist pin disk forming part of the power trans- 60 mitting gearing.

Fig. 5 is a section on the line 5—5 of Fig. 4 showing the shifting lever.

Fig. 6 is a face elevation with some parts in section of one of the trunnion castings 65 supporting the washing machine body and also showing some parts connected thereto.

Referring to the drawings there is shown a frame 1 which may be conveniently made of angle iron, although any particular material is not demanded. This frame is supported upon legs 2 which may be conveniently arranged at the corners of the frame, since the latter is ordinarily of rectangular outline. Adjacent and connected to the 75 frame 1 is another frame 3 supported upon legs 4, the frame 3 being designed to support certain devices employed in the operation of clothes washing.

On opposite sides of the frame 1 about 80 midway of the length of the latter, standards 5 are erected and each standard at its upper end is provided with a journal bearing 6.

There is also provided a washing machine body 7 which may be of the general character and operate similarly to the washing machine body shown and described in Letters Patent No. 981,169, granted to me on January 10, 1911. On one side the body 7 has fast thereto a casting 8 with divergent 90 arms and provided with a trunnion 9 entering a respective one of the journal bearings 6. On the opposite side of the body 7 is another casting 10 shown more particularly in Fig. 6, where it will be observed 95 that the casting is formed of three arms 11, 12, meeting at a common center where the casting is provided with a trunnion 13 adapted to the respective journal bearing 6.

Both castings 8 and 10 are shown in the 100 drawings as of web and flange type, but the invention is not confined to any particular arrangement in this respect. The arms 11 and 12 form convenient means for attaching the casting 11 to the body 7 in such manner 105 as to widely spread the support, wherefore there is little liability of any of the parts loosening under the strain of operation.

The arm 12, in the installed position of the machine, extends downwardly below the bottom of the body 7 and terminates at the end remote from the trunnion 13 in a pin 14. The arm 12 is also formed with an offset bracket 15 terminating in a pin 16 at a point more remote from the trunnion 13 than is the pin 14.

The standards 5 and trunnions 9 and 13 are so located that the body 7 is situated within the frame 1 in a manner to permit rocking of the body 7 in said frame on an axis corresponding to the axes of the trunnions 9 and 13 which are in alignment and located intermediately of the height of the body 7, in the installed position of the machine, and substantially midway of the length of said body 7.

Connected to the pin 14 are adjacent eye 20 ends of two springs 17, the other ends of these springs being made fast to one of the side bars of the frame 1 by eye bolts 18, or in any other convenient manner. When the springs 17 are properly attached they are 25 each under sufficient extension to hold the body 7 approximately level, but the body 7 may be rocked in either direction on its trunnions by a properly applied force, one spring then expanding on the rocking of 30 the body in one direction with the other spring contracting. However, the normal tendency of the springs is to maintain the body in a level position and to return it to such level position when rocked in either direction therefrom, wherefore the springs 17 35 act as equalizing springs.

Attached to the body 7 is a handle socket 19 which may be conveniently located midway between the ends of the body 7 on the 40 same side as the casting 10, and the socket 19 is designed to receive a manipulating handle 20, which, however, may be removed from or applied to the socket as desired.

Considering the structure so far described, 45 washing may be performed by simply rocking the body 7 by force applied by hand to the handle 20, and if desired the springs may remain in position more or less facilitating the action of the body by hand only. 50 If desired, the springs may be detached by slipping the adjacent ends from the pin 14 whereupon the springs will simply hang idly from the eye bolts 18.

When the machine is actuated by power, 55 there is provided a pitman 21 which at one end is formed with a clip 22 adapted to engage the pin 16 and is connected to the pitman 21 by a hinge connection shown in the drawings as in the form of a bolt 23.

60 The other end of the pitman 21 is similarly connected to a wrist pin 24 on a wrist pin disk 25, which latter is formed with a hub 26 provided with a circumferential groove 27 and at the end remote from the 65 disk with a diametric recess 28.

The hub 26 is mounted to slide on a shaft 29 provided with journal bearings 30, 31 near the opposite ends and carried by suitable bars 32, 33 fast to the frame 1 by other cross bars 34.

In close parallel relation to the shaft 29 is another shaft 35 provided with journal bearings 36, 37 on the bars 32, 33, respectively. The shaft 29 carries a gear wheel 38 with which there is in mesh a pinion 39 fast on the shaft 35. At the end of the shaft 35 remote from the bar 32 is a drive pulley 40, the shaft 35 being long enough for the purpose. The pulley 40 may be a grooved pulley as shown, or of any form suitable to receive a driving belt. In the particular showing of the drawings there is provided a belt 41 carried to a pulley 42 on the armature shaft of an electric motor 43 in turn mounted upon the bar 33 by means of clip plates 34^a and clamp bolt 35^a. By this means the motor 43 may be adjusted along the bar 33 and there clamped in order to take up any slack in the belt 41. The motor 43 provides a convenient driving unit wherever electric power is available, but where electric power is not available some other convenient means of supplying power may be provided, as is customary. When the motor 43 is running the shaft 35 is driven therefrom by means of the belt 41 and pulley 40, and motion is transmitted from the shaft 35 to the shaft 29 by the pinion 39 and gear wheel 38. The disk 25 is movable lengthwise of the shaft 29 on the end of the latter on which it is mounted, and this is accomplished by means of a manipulating lever 44 pivotally mounted on a bracket 45 which may form part of the structure of the journal bearing 30. The lever 44 terminates in a yoke 46 with pins 47 taking in the groove 27. Traversing the shaft 29 is a pin 48 so situated that the hub 26 of the disk 25 may be moved toward the pin 48 until the latter is housed in the recess 28, whereupon the disk 25 and shaft 29 are coupled together or may be uncoupled at any time by a suitable manipulation of the lever 44. This constitutes a convenient means whereby the disk 25 may be coupled up to the shaft 29 or uncoupled therefrom, and when the disk and shaft are coupled, then power is transmitted from the motor 43 through the gearing connections to the pitman 21, which latter is actuated by the wrist pin 24, thus causing 110 the washing machine body 7 to rock on its trunnions alternately expanding and releasing the respective springs 17.

By a suitable proportioning of the parts a relative high speed of the motor, which customarily runs at high speed, is reduced at the disk 25 to a suitable speed, so that the body 7 may rock at a speed of say, forty or forty-five complete oscillations per minute. However, any particular rate of 130

speed is not obligatory and will depend upon conditions to be met.

Since it is customary to supply washing machines with clothes wringers, there is shown in the drawings a clothes wringer 49 which may be considered as of an approved type, the wringer being supported upon a sleeve 50 and bracket 51 with the sleeve 50 traversed by a shaft 52 carrying a bevel pinion 53 meshing with another bevel pinion 54 on a shaft 29. Power to the moving parts of the wringer is obtained from the shaft 52 by suitable gearing inclosed in a casing 55, but as these features 15 form no part of the present invention, no particular showing or description is deemed necessary. It may be stated, however, that the mounting for the wringer is capable of rotation upon the upright axis of the shaft 20 52 into different positions, the frame 3 constituting a convenient means for supporting tubs or other receptacles for the clothes after passing through the wringer, and for containing clothing removed from the washing machine body 7 before being passed 25 through the wringer, if such be desirable.

With the present invention rotary motion of the prime mover 43, which may represent an electric motor or any other suitable 30 actuating device, is converted by means of the gearing into rocking motion at the washing machine body 7 with the gearing connections including means for connecting or disconnecting the washing machine body at 35 will from the prime mover, thus avoiding the necessity of stopping the latter when it is desired to temporarily stop the oscillation of the body 7. Again, the structure permits the disconnecting of the washing 40 machine body from the driving gearing, so that the washing machine body may be manipulated by hand through the medium of the handle 20 if such be desirable.

The operative or active mechanism may 45 include both the washing machine body and the wringer, and the washing machine body may be of a rocking or vibratory construction held to a neutral position by opposed or equalizing springs, so that when the rockable body is displaced from the position to 50 which it is normally constrained, this movement is resisted by one spring and assisted by the other, and these springs are connected to the body at some distance below the axis 55 of rocking in the installed machine. Moreover, the connection for the springs forms part of a trunnion device constituting one trunnion support of the rockable member.

In order to readily empty the body 7 of 60 water, when desired, it is provided with a drain valve 56 with a suitable length of flexible pipe 57 connected thereto.

What is claimed is:—

1. The combination with a rockable member, of an arm on the rockable member ex-

tending radially from the axis of rocking, opposed springs both connected to the arm in spaced relation to the axis of rocking and yieldably constraining the rockable member to a central or neutral position, driving 70 means, gearing connected to and actuated by the driving means, reciprocatory means interposed between the arm and the gearing, and means for connecting the reciprocatory means to and disconnecting said means from 75 the gearing, at will.

2. The combination with a rockable member having a substantially horizontal axis of rocking located intermediate of the height of the rockable member, of an arm 80 on the rockable member extending downwardly from the axis of rocking, opposed springs both connected to the lower portion of the arm, and driving means also connected to the lower portion of the arm. 85

3. In a washing machine, the combination with a rockable washing machine body having its axis of rocking within the confines of the body, an arm fast to the body and extending downwardly in the installed 90 position of the body from the axis of rocking, oppositely acting springs both connected to the arm at the lower portion thereof, and driving means also connected to the arm at the lower portion thereof for rocking the body to simultaneously extend one 95 spring and release the other.

4. The combination with a rockable member, of an arm fast to the rockable member and extending downwardly from the axis 100 of rocking, a reciprocable member connected to the arm at the lower portion of the latter, oppositely acting springs also connected to the arm at the lower portion of the latter, a rotatable member to which the reciprocable member is connected, driving means, gearing between the driving means and the rotatable member, and means for connecting the rotatable member to and disconnecting it from the driving means, at 105 will. 110

5. In a washing machine, a rockable body member having trunnions in the axis of rocking with said axis located between the ends, top and bottom of the body member, 115 an arm fast to the body member and extending downwardly from the axis of rocking, oppositely-directed springs connected at their adjacent ends to the lower portion of the arm, and driving means also connected 120 to the lower portion of the arm and operable to rock the body member to stretch the springs one at a time in alternation.

6. The combination with a rockable member having trunnion journals intermediate 125 of its height, of an arm fast to a trunnion journal and extending downwardly therefrom, opposed equalizer springs both connected to the lower end of the arm, a pitman also connected to the lower por- 130

tion of the arm, and driving means for the pitman.

7. The combination with a rockable member having trunnion journals intermediate 5 of its height, of an arm fast to a trunnion journal and extending downwardly therefrom, opposed equalizer springs connected to the lower portion of the arm, a pitman also connected to the lower portion of the 10 arm, a rotary crank disk for actuating the pitman, and driving mechanism for the crank disk including a prime mover and means for connecting the crank disk to and disconnecting it from the driving mechanism, at will.

8. A machine having active members including a rockable member with an arm extending from the axis of rocking, a frame carrying the active members, opposed 20 springs connected to the arm and to the frame and tending to maintain the rockable member in a centralized position, a pitman connected to the arm, a crank disk to which the pitman is connected, a shaft upon which the crank disk is mounted and along which it is movable, means for moving the crank disk along the shaft, clutch means for connecting the crank disk to and disconnecting it from the shaft by movements of the crank disk along the shaft, another shaft, intermeshing gearing between the shafts, and means on the second shaft for the application of power thereto.

9. A machine having active members including a rockable member with an arm extending from the axis of rocking, a frame carrying the active members, opposed 30 springs connected to the arm and to the frame and tending to maintain the rockable member in a centralized position, a pitman connected to the arm, a crank disk to which

the pitman is connected, a shaft upon which the crank disk is mounted and along which it is movable, means for moving the crank 45 disk along the shaft, clutch means for connecting the crank disk to and disconnecting it from the shaft by movements of the crank disk along the shaft, another shaft, intermeshing gearing between the shafts, and a 50 prime mover and connections between the prime mover and the second shaft for the actuation of the latter.

10. A machine having active members including a rockable member with an arm extending away from the axis of rocking, a frame carrying the active members, opposed 55 springs connected to the arm and to the frame and tending to maintain the rockable member in a centralized position, a pitman 60 connected to the arm, a crank disk to which the pitman is connected, a shaft upon which the crank disk is mounted and along which it is movable, means for moving the crank disk along the shaft, clutch means for connecting the crank disk to and disconnecting it from the shaft by movements of the crank disk along the shaft, another shaft, intermeshing gearing between the shafts, and a 65 prime mover and connections between the prime mover and the second shaft for the actuation of the latter, said prime mover comprising an electric motor mounted on the frame and movable therewith along with belt 70 connections between the motor and the second-named shaft.

In testimony, that I claim the foregoing as my own, I have hereto affixed my signature in the presence of two witnesses.

FRANK BYRON CHURCHILL.
